UNITED STATES PATENT OFFICE.

JOSEPH McCONNELL, OF PITTSBURG, AND ROBERT W. MILLER, OF ALLEGHENY CITY, PENNSYLVANIA.

OIL-WELL CASING.

SPECIFICATION forming part of Letters Patent No. 367,052, dated July 26, 1887.

Application filed January 20, 1887. Serial No. 224,860. (No model.)

To all whom it may concern:

Be it known that we, JOSEPH McCONNELL, of Pittsburgh, and ROBERT W. MILLER, of Allegheny City, all in the county of Allegheny and State of Pennsylvania, have invented a new and useful Improvement in Oil-Well Casings; and we do hereby declare the following to be a full, clear, and exact description thereof, reference being had to the accompanying drawings, forming part of this specification, in which—

Figure 1 is a vertical axial section of the lower part of an oil-well casing showing our improved packer and sustaining devices. Fig. 2 is a similar view, showing the packer and the sustaining devices in the position which they occupy when projected against the sides of the well. This figure also shows the retaining-cap 16 separated from the casing. Fig. 3 is a vertical axial section on the line $x-x$ of Fig. 1. Fig. 4 is a bottom plan view of the retaining-cap which we employ for confining the sustaining devices of the casing until the casing has been lowered to the proper position in the well. Fig. 5 is a plan view illustrating the mode of manufacture of the cap shown in Fig. 4. Fig. 6 is a vertical cross-section on the lines $y-y$ of Figs. 1 and 7. Fig. 7 is an enlarged vertical axial section of the lower part, 13, of the packer, with the cap 16 removed. Figs. 6 and 7 are drawn on the same scale, the other figures are on a smaller scale.

Like symbols of reference indicate like parts in each.

In drilling oil-wells, in order to keep the water from the upper strata of earth from flowing down to the oil-producing strata, and thereby filling up the hole and driving back the oil, it has been customary to insert a casing or tube into the hole, extending from the top down below the water-strata. A packing of rubber or other suitable material is often fitted around the casing at a point which, when the casing is set in place, is below the lowest water-veins. The compression of this packing between the casing and the sides of the hole seals the space between them and prevents the descent of the water.

It is the object of our invention to improve the construction of such packing and to pro-

vide improved means for supporting the casing in the well at any desired point.

In the drawings, Figs. 1 and 2 show the casing of the oil-well. It consists of pipe sections or tubes which are screwed together and let in the well in the usual way.

2 is one of the lower sections of the casing, the upper end of which fits around the section 3 above it, and is adapted to slide telescopically thereon. It is confined to the section 3, so that when the latter is lifted it will carry the section 2 with it, by means of a hook or flanged joint, 4.

5 is the packer, which consists of a simple rubber tube, whose sides are substantially the same thickness from top to bottom. This tube is fitted around the section 3 and is secured thereto by rivets 6. Its upper end fits against a seat or shoulder on the section 3, which is preferably constituted by the lower end of a connecting-nipple, 7. The upper edge of the casing-section 2 is beveled and fits underneath the lower end or facing of the packer-tube, which for this purpose is correspondingly beveled. To the lower end of the section 2 of the casing is screwed a tube-section, 8, which is provided with a series of catches, 9, arranged around its periphery and adapted to engage the sides of the well and thus support the casing. To accommodate these catches, the lower part of the section 8 is made of somewhat less thickness than the upper part. This affords a seat or shoulder against which the upper or butt ends of the catches bear. The catches are pivoted to the section 8 by pintles 10, and are adapted to be normally flush with the sides of the casing, as shown in Fig. 1. The lower ends of the catches are beveled. 11 is a tubular section, which is fitted around the lower part of the section 8 and is arranged to slide telescopically thereon, the limits of its motion being defined by pins 12, attached to the inner section, 8, and fitting in vertical slots in the outer section, 11. The upper edge of the section 11 is preferably beveled conformably to the bevel of the lower edge of the catches. Screwed to the bottom of the section 11 is the lowest section, 13, of the casing. A part of it is beveled or made cone-shaped on the outside, as at d , Figs. 1, 2, and

100

7, the bevel terminating abruptly, so as to afford a seat, *e*, at its base. Around this beveled portion *d* and normally resting on the seat *e* are a number of segmental curved pieces, 5 18, whose inner or concave sides are beveled and curved conformably to the curvature and bevel of the circumference of the beveled portion *d* of the section 13. When placed edge to edge on the seat *e*, these pieces 18 extend 10 around the periphery of the section 13. The parts 18 are intended to act as wedges to confine the casing against the sides of the well. In order to guide them in their vertical movements and to prevent them from moving laterally, each is provided with a vertical guide-rod, which is fastened to the lower end of the casing-section 13 at the seat *e*, and thence extends upward through the wedge 18 beside the casing and terminates in an angle or hook, 19, 15 which is fitted in a hole in the side of the casing. The several wedges 18 are provided with dogs or catches 14, which are set in recesses in the wedges, and are pivotally mounted therein at their upper ends. These wedges 20 have springs 15 on their inner sides for projecting them. The dogs 14 are normally held within their recesses by means of a cap, 16, which fits over the bottom of the casing-section 13 around the catches. In Fig. 7 this cap 25 is omitted for clearness of illustration.

The normal position of the parts as they are when the casing is being lowered into the well is shown in Fig. 1. When the casing has been lowered to the desired point, a weight is 30 dropped into it from the top of the well, which, striking upon the bottom cap, 16, knocks it off the lower end of the casing and releases the catches 14, which are then immediately projected by the springs 15 and assume a down- 35 wardly and outwardly inclined direction. The weight of the casing will cause the ends of these catches, which may be suitably roughened, to bite upon the sides of the well and to uphold the wedges 18, Fig. 2. Then, as the 40 casing descends, the wedges, being fixed by the dogs, will slip upward on the beveled portion of the section 13 and will be forced outwardly thereby until they engage the sides of the hole, where they become jammed between 45 it and the casing, so locking the latter firmly in place, as shown in Fig. 2. During this upward motion the wedges are guided by the rods 19, whose positions are illustrated by the full lines in Figs. 1 and 2 and by the 50 dotted and full lines in Fig. 7. After the wedges 18 have been jammed, the weight of the casing-sections above, bearing on the sections 2 and 8, will cause the section 8 to slip down inside the section 11, the beveled upper 55 end of which, engaging the beveled ends of the catches 9, projects them against the sides of the well, as shown in Fig. 2. Both the wedges 18 and the catches 9 having now become fixed, they will sustain the casing in place. 60 At the same time the downward pressure of the casing on the section 3 will cause the latter to slip down inside the section 2, and the be- 65

veled upper end of the latter section, acting as a wedge upon the packer ring, will force the latter outward against the sides of the well, 70 as shown in Fig. 2, so as to cut off the water from the upper strata from the well below.

If desired, the catches 9 may be dispensed with and the wedges 18 used alone. The form of dog 14 used in connection with the wedges 75 may be modified, it being necessary only that there shall be some device to give the wedges a first hold on the sides of the hole in order to bring the wedges into operation.

The packer when thus constructed has many 80 advantages. All the working parts may be put on the outside, so as not to contract the inside diameter of the casing, and thus interfere with the operation of the drilling-tools. The packer is firmly supported; but when de- 85 sired to be drawn out the parts afford very little resistance. The device is also very light and simple in its construction, but is of great strength.

We shall now describe certain details of construction of the apparatus, which constitute 90 important features of our invention. In order to prevent the lower edge of the packer-tube 5 from being torn or abraded by the wedging action of the upper end of the section 2, we 95 surround it by a leather ring or facing, 17. The construction of the packer-tube, whose side is of substantially constant thickness from top to bottom, instead of the cone-shaped packer-rings heretofore employed, is impor- 100 tant, and materially increases the efficiency of the device.

In Figs. 4 and 5 we show a simple and convenient mode of making the cap 16, which confines the lower catches, 14. We stamp out a 105 piece of tin or sheet-iron of the shape shown in Fig. 5, having a longitudinal strip, *a*, and arms *b* projecting therefrom at right angles. The strip *a* is bent into a circular shape, and the arms *b* are then bent inwardly toward the center of the bottom of the cylinder so formed, and are there confined by rivets *c*. This produces the necessary shape, and is a cheap and simple mode of construction.

We do not desire to limit ourselves to the 115 exact arrangement of the casing-sections shown in the drawings. Many of them, which we have shown in several parts secured together, may be made in single pieces, or the number of the parts may be increased, if desired.

What we claim is—

1. A well-casing having external downwardly-directed pivotally-mounted supporting-catches, and a sliding section, 11, arranged to engage and project the catches, substantially as and for the purposes described.

2. The pivotally-mounted supporting-catches 9, in combination with the sliding wedge or section 11, secured to the casing by pins working in slots, so as to afford a limited motion to the wedge, substantially as and for the purposes described.

3. An oil-well casing having external catches capable of projection, in combination with a

removable cap fitting over the casing and confining the catches, substantially as and for the purposes described.

4. An oil-well casing having external catches capable of projection, in combination with a removable cap fitting over the casing and confining the catches, and springs for projecting the catches, substantially as and for the purposes described.

10 5. A rubber packing ring having its edge faced with leather, substantially as and for the purposes described.

6. The combination, with a well-casing, of a series of segmental wedges fitted around a tapering portion of the outside of the casing and arranged to move vertically thereon, said tapering portion increasing in diameter upwardly, whereby downward motion of the casing relatively to the wedges will project the latter, substantially as and for the purposes described.

15 7. The combination, with a well-casing, of a series of segmental wedges fitted around a tapering portion on the outside of the casing and arranged to move vertically thereon, said tapering portion increasing in diameter upwardly, whereby downward motion of the casing relatively to the wedges will project the latter, and catches on the wedges arranged to engage the sides of the well, substantially as and for the purposes described.

20 8. The combination, with a well-casing, of a

series of segmental wedges fitted loosely around a beveled portion of the casing, whereby downward motion of the casing relatively to the wedges will project the latter, and vertical 35 guide-rods 19, passing through the wedges and extending above the same, substantially as and for the purposes described.

9. The combination, with a well-casing, of a series of segmental wedges fitted loosely around a beveled portion of the casing, whereby downward motion of the casing relatively to the wedges will project the latter, and spring-catches on the wedges arranged to engage the sides of the well, substantially as and for the 40 45 purposes described.

10. The combination, with a well-casing, of projectible catches and the removable cap 16, confining the catches, said cap being constructed of a strip of metal, *a*, and arms *b*, projecting therefrom at right angles, the said strip being bent into circular shape and the arms *b* bent inwardly toward the axis of the cylinder thus formed and held together, substantially as and for the purposes described.

50 In testimony whereof we have hereunto set our hands this 14th day of January, A. D. 1887.
